UNITED STATES PATENT OFFICE.

CHARLES H. CROSIER, OF WEST SPRINGFIELD, MASSACHUSETTS, ASSIGNOR TO MITTINEAGUE PAPER COMPANY, OF MITTINEAGUE, WEST SPRINGFIELD, MASSACHUSETTS, A CORPORATION OF MASSACHUSETTS.

MANUFACTURE OF CARD OR PAPER SHEETS.

SPECIFICATION forming part of Letters Patent No. 767,329, dated August 9, 1904.

Application filed December 17, 1903. Serial No. 185,492. (No specimens.)

To all whom it may concern:

Be it known that I, CHARLES H. CROSIER, a citizen of the United States of America, and a resident of West Springfield, in the county of 5 Hampden and State of Massachusetts, have invented certain new and useful Improvements in Manufacture of Card or Paper Sheets, of which the following is a full, clear, and exact description.

10 The object of this invention is to produce a paper or cardboard sheet having a mottled or marble-like appearance at its face notwithstanding the fact that the sheet or sheets making the face or faces of the card or composite 15 sheet are of uniform color throughout the entire substance and area thereof.

The invention consists in a composite sheet or card composed of a body layer of paper and a face layer of paper adherently connected to the body layer, the body layer being of a different color than the face layer and the latter having in different portions thereof different degrees of translucency, whether this latter characteristic be acquired by making 25 the face-constituting sheet of unequal thickness in different places or so treating the face-constituting sheet, which might be of uniform thickness, chemically or otherwise, whereby it has spots or patches distributed throughout 30 its area less opaque than the relatively intermediate spots or patches.

A cardboard sheet of the character described is in a manner illustrated in the accompanying drawings, in which— 35 Figure 1 is a perspective view, a portion of one of the face-constituting sheets being represented as partially stripped and turned back from the body-constituting layer. Fig. 2 is a sectional view through the thickness of the 40 paper, on a very much enlarged scale, as taken on the line 2 2, Fig. 1. Fig. 3 is a sectional view similar to Fig. 1, designed to represent the provision in the composite sheet of the face layer having a uniform thickness, with, 45 however, varying degrees of translucency for the acquirement of substantially the same mottled appearance.

In the drawings, A represents the body layer or sheet of paper, and B the face layer, the

latter having at different spots or portions of 50 its area different degrees of semitransparency or translucency, the face layer being of a different color than that of the body layer and stuck thereto by paste or other suitable adhesive. 55

As most practicably carried out generally the face layer is rendered variably translucent, as aforesaid, by having variations in its thickness at different spots distributing throughout its area and, as represented in Fig. 2, the 60 thicker portions *a* being more opaque or less translucent than the thinner portions *b*, so that the color of the body layer A, which is different from that of the face layer, may be more or less visible at the face of the sheet through 65 the less opaque portions.

The card may have a back face-sheet B² as well as a front face-sheet B and of the same character.

Any colors or combinations thereof may be 70 observed in the manufacture or selection of the sheets which are combined to make the new card. For instance, the body-sheet may be very dark, as black, slate, gray, &c., and the face sheet or sheets may be white or of 75 any color or tint strongly contrasting with that of the body-sheet.

In Fig. 3 the face sheet or sheets are represented for the acquirement of substantially the same visual effect by being made of uniform thickness having opaque spots *a*² and relatively intermediate semitransparent spots *b*² therein, which may be produced by subjecting different portions of the sheet of paper to the action of chemicals, which, without in any 80 manner coloring the sheet, makes a multiplicity of segregated small areas therein much 85 more translucent than the commingled areas not treated.

I am of course aware that paper sheets have 90 been produced having mottled, marbled, or variegated appearance produced by the employment of color either intimately incorporated in the fiber of the paper in the manufacture thereof or afterward applied on the 95 surface thereof; but this invention is in no wise dependent on any such method of production.

Having thus described my invention, what I claim, and desire to secure by Letters Patent, is—

1. A card or composite sheet consisting of a body layer of paper, and a face layer of paper, adherently connected thereto, the body layer being of a different color than the face layer, and the latter having, in different portions thereof, different degrees of translucency.

2. A card or composite sheet consisting of

a body layer of paper, and a face layer of paper adherently connected thereto, the two layers being of different colors and the face layer being of unequal thickness in different portions thereof. 15

Signed by me at Springfield, Massachusetts, in presence of two subscribing witnesses.

CHAS. H. CROSIER.
